RUBBER SOLE FOR SANDALS

Max Albert Westheimer, New York, N. Y.

Application October 22, 1938, Serial No. 236,371

2 Claims. (Cl. 36—11.5)

The invention relates to a sandal having a rubber sole and particularly to an arch supporting sandal.

Many devices for the support of the instep arch 5 are known and used with shoes or boots.

In the majority of these cases the arch-supporting means consist of suitably shaped metal plates or pads and cushions of resilient material and many suggestions and attempts have been 0 made to properly connect these arch supports with the soles of the shoes, one of the most important requirements in this connection being that the dislocation and the displacement of the arch support is prevented and its fixed position 5 is ensured.

This problem of suitably and properly locating the arch support however bears a fully different aspect if the support is to be used in a sandal.

A sandal by its very nature is not a tight fitting 20 article of footwear and is loosely connected with the foot by means of straps. Consequently due to the loose fit a separate arch support of the ordinary type can not be held in place.

It is the object of the invention to provide for 25 the proper wearing relationship between the foot, the arch support and the sole.

With this purpose in view the rubber sole is shaped and manufactured according to this invention integral with the arch support.

It is a further object of the invention to provide improved means for accommodating and fastening the tying straps. This is accomplished 30 by providing peculiar recesses premolded in the sole.

It is a further object of the invention to provide a sole integrally molded in conformity with the shape of the foot.

It is a further object to improve the fastening 40 of the straps to the sole so that the same will merge into the sole with no undue protrusions noticeable to the wearer.

All these improvements of the rubber sole forming the subject of the invention are effected during the manufacture or vulcanization thereof 45 and the rubber sole therefore is a ready made, arch supporting unit for mounting on the same the further accessories of the sandal.

The invention is illustrated by way of example in the annexed drawings, of which

Fig. 1 shows a top view of the sandal,

Fig. 2 shows a side view of the same,

Fig. 3 a sectional view according to line 3 to 30 of Fig. 1,

Fig. 4 a top view of the rubber sole,

Fig. 5 a side view of the same,

Fig. 6 a sectional view according to line 6—6 of Fig. 4,

Fig. 7 a sectional view according to line 7—7 of Fig. 4,

Fig. 8 a sectional view according to line 8—8 of Fig. 1.

The sole 1 made of rubber has an outwardly curved elevation 2 on its inside surface 3 which in the location of the instep arch ascends from the middle part of the sole and extends to the 10 inner side of the same the outside curvature of this elevation 2 corresponding to the instep arch.

A series of recesses 4 are formed in the inner surface of the sole; these recesses exactly correspond to the shape of the end portion of the tying straps 5 which in order to be connected to the sole are inserted into these recesses.

The dimensions and the depth of the recesses which may be arranged at suitable places are chosen in such manner that when the straps are 20 inserted they lie flush with the upper surface of the rubber sole.

The toe part 6 of the sole is preferentially upwardly bent and a concave curvature 7 corresponding to the shape of the heel part of the 25 foot is provided in the inside surface of the sole.

The straps are fastened to the sole by means of hollow rivets 9; for this purpose holes 10 and 30 perforated washers 11 are provided in the sole during the manufacture and vulcanisation thereof. The end portions of the straps are inserted into the recesses and the rivets are driven through the same, the holes of the sole and the washers; the ends of the rivets protruding within the sole over the washers are flattened out over the outside 35 of the same by a suitable pressing tool.

Instead of using rivets the straps may also be sewed to the soles; the seams are preferentially located inside of the soles so that they are not 40 visible from the outside.

After fastening the straps in the described or any other suitable manner the sole is covered by a leather blank 14 of which the shape corresponds to the shape of the sole. An elevated roughened marginal portion 8 is provided on the 45 inside surface of the sole. The depth of the strap receiving recesses is such that the straps are flush with the inner surface of the sole; if covered by the leather blank a uniform continuous walking surface is created therefore and the 50 straps will not create undue pressure on the foot of the wearer.

The heel 13 which also is an integral part of the sole extends with its inner front edge 12 up to the arch supporting elevation 2.

5 The outside or the walking surface of the sole may be roughened in order to form an imitation of the crude or the so-called "crêpe" rubber, or a thin sheet of this rubber may be cemented to the walking surface of the sole.

With the integral arch supporting elevation, the integral heel, the recesses in the sole for the tying straps and the fastening means inside of the sole of the latter forms a ready-made arch-
10 supporting mounting unit.

What I claim is:

1. A rubber outsole for sandals comprising a heel and an arch support integral with said sole, recesses in the upper face of said sole for accommodating the ends of fastening straps, said recesses being of such a depth as to accommodate said straps in flush relationship with the top surface of said sole, holes for receiving hollow rivets passing vertically through said sole and 15 into the said recesses, said rivets being adapted to be flattened out over the ends of the straps to be received in the recesses, an elevated marginal
20

portion on said sole, a blank covering the inside surface of the sole and having its top face flush with the top face of said marginal portion, said marginal portion extending continuously around the sole, said sole thereby forming a ready-made 5 mounting unit for the fastening straps and insuring the proper location of the arch support in relation to the heel and to the straps.

2. A sandal comprising a rubber sole having an arch support integral therewith, recesses in its 10 upper face adapted to receive the ends of fastening straps with substantially the entire ends of said straps in flush relationship to the upper face of said sole, said sole having a narrow, continuous margin around its upper face elevated above 15 the body of said rubber sole, foot engaging straps having their ends secured in the recesses, and a leather central element disposed in the recess formed by said margin, the top face of said central element being flush with the top of the margin. 20

MAX ALBERT WESTHEIMER.
